UNITED STATES PATENT OFFICE.

JOHN M. FRANK AND ARTHUR G. SUTCLIFFE, OF CHICAGO, ILLINOIS, ASSIGNORS TO
ILG ELECTRIC VENTILATING COMPANY, OF CHICAGO, ILLINOIS, A CORPORATION
OF LOUISIANA.

VENTILATING APPARATUS.

Application filed April 14, 1926. Serial No. 101,859.

This invention, in its chief intended application, relates to ventilating apparatus of a well-known type which comprises a rectangular frame mounted in or over an opening in the wall of a building, a series of horizontal gravity closing shutter vanes pivoted in said frame and connected for simultaneous opening and closing movements, and a motor-driven fan mounted opposite to said vanes and, when in operation, opening the latter by the blast of air created thereby.

Ventilating apparatus of the above-described type is illustrated in Letters Patent 15 to Robert A. Ilg No. 1,482,398, dated February 5, 1924, and No. 1,525,649, dated February 10, 1925. In the last-mentioned patent there is disclosed an automatic device for locking the shutters in closed position when 20 the fan is idle and automatically releasing the shutters when the fan is started in operation, the blast created by the fan actuating the locking mechanism to release position.

The main utilities of a shutter lock are to 25 prevent rattling of the shutter vanes and partial opening of the same under the influence of outside winds or interior drafts tending to flow through the opening, and also to maintain the opening closed against weather 30 influences when the use of the ventilator is not desired or required. Our present invention relates mainly to a new and improved shutter lock that is not dependent upon the blast of the fan for its release but is manually actuated to both locking and release 35 position, and one object of the invention is to provide a very simple and efficient shutter lock of the character last described. Another object is to provide, in a ventilating 40 apparatus of the type specified, a shutter locking and releasing device that may be actuated from and simultaneously with the motor switch, so as to release the lock when the current is turned into the motor and set 45 the lock when the current is turned off.

Our present invention, its mode of operation, and the advantages inhering therein will be readily understood by persons skilled in the art as the same becomes better understood by reference to the following detailed description, taken in connection with the accompanying drawings wherein we have illustrated one practical and approved em-

bodiment of the principle of the invention, and in which—

Fig. 1 is an outer side elevation of the frame and shutters showing our improved locking device in shutter-locking position;

Fig. 2 is a side elevation, in vertical section through the wall or panel in which the device is mounted;

Fig. 3 is an enlarged fragmentary vertical section through the lower right hand corner portion of the shutter frame, on the line 3—3 of Fig. 4; and

Fig. 4 is a fragmentary vertical section in the plane of the line 4—4 of Fig. 3.

Referring to the drawing, 5 may be assumed to represent the external wall of a room to be ventilated, the same having an opening formed therein over which, on the outer side of the wall, is attached a rectangular metal shutter frame 6. In and between the opposite vertical members of the frame 6 are mounted, on horizontal spindles 7, a group of shutter vanes 8. These vanes are connected for simultaneous opening and closing movements by elbow levers 9, the lower arm of each lever lying in a pocket 10 formed on the rear side of the shutter vane and its upper arm being pivoted to a vertically disposed link or shift rod 11 lying inwardly of one vertical side wall of the frame 6. To the inner side of the building wall 5 is secured a frame 12 in which is mounted an electric motor 13, the shaft of which carries a direct-driven ventilating fan 14.

The shutter mechanism thus far described is or may be substantially identical with that disclosed in the Letters Patent No. 1,482,398 above referred to.

Describing now our improved shutter locking mechanism, on the lower end of the vertically disposed link or shift rod 11 is a short horizontal extension or foot 15; the rod 11 and its foot 15 preferably being continuous or integral and taking the form of an angle bar. The joint between the vertical and horizontal members 11 and 15 may be reinforced by a gusset plate 16. The horizontal limb of the foot member 15 is apertured and slidably mounted on a vertical guide or steady rod 17 mounted in the bottom horizontal member of the frame 6.

On the inner side of the wall 5 is mounted

an ordinary electric snap switch 18 which opens and closes the circuit through the fan motor 13. 19 is the switch button fast on the outer end of the usual switch stem or shaft 20. In accordance with our present invention this stem or shaft 20 is extended through the switch and through a suitable hole and bushing 20' in the wall 5 to a point within the shutter frame 6; and on the inner end of the switch shaft 20 is mounted a transverse bar 21 formed on both ends as wiper cams 22 which lie beneath and in the vertical plane of the foot 15.

Figs. 3 and 4 show in full lines the locking device in shutter-locking position, wherein in the lifting and locking bar 21 is vertical and supports the link 11 in elevated position, which corresponds to the closed position of the shutter vanes. In this position of the lifting and locking bar the motor circuit is open at the switch 18. A quarter turn of the switch button closes the motor circuit and at the same time swings the lifting and locking bar 21 to the horizontal position indicated by dotted lines in Fig. 3, which leaves the link 11 free to drop and the shutter vanes to open under the blast of the fan aided by the gravity of the link. The next quarter turn of the switch button, which opens the motor circuit again swings the lifting and locking bar 21 to vertical position, such movement raising the link 11 and closing and locking the shutter vanes. By thus directly connecting the shutter locking device to the motor switch, the necessity of separate manually operable devices for energizing and de-energizing the motor and for throwing and releasing the shutter lock is avoided. The rounded cam-shaped ends 22 of the locking bar serve to effect the final full closing and locking movement of the shutter vanes.

We have herein shown and described one simple and practical physical embodiment of the principle of the invention, but manifestly changes in structural details and form and arrangement of the parts may be resorted to without departing from the principle of the invention or sacrificing any of the advantages thereof. It is also evident that the described locking means may be usefully employed without the fan and its motor and with a shutter having a single vane. Hence we reserve all such variations and modifications as fall within the spirit and purview of the appended claims.

We claim—

1. In a ventilating appliance of the character described, the combination of a frame, a group of horizontal shutter vanes hinged in said frame, levers connected to said vanes respectively, a vertically disposed link connecting said levers for simultaneous movement, said link having a horizontal foot, a rotatable lifting and locking bar underly-

ing said foot in sliding contact with the sole of the latter, and manually operable means for turning said bar.

2. In a ventilating appliance of the character described, the combination of a frame, a group of horizontal shutter vanes hinged in said frame, levers connected to and extending rearwardly of said vanes respectively, a vertically disposed link pivotally connected to said levers, said link having a horizontal foot, a rotatable lifting and locking bar underlying said foot formed with cam-shaped ends adapted to alternately engage with and lift said foot as said bar is rotated, and manually operable means for turning said bar.

3. The combination with a fan, and a motor for driving the same, of a pivoted shutter, means for locking the shutter in closed position, and a single means for simultaneously starting said motor and releasing said shutter locking means.

4. In a ventilating appliance of the character described, the combination of a frame, a group of shutter vanes hinged in said frame, a fan mounted behind said vanes, an electric motor for operating said fan, a switch controlling the circuit of said motor, and mechanism actuated by an element of said switch serving to lock said vanes in closed position when said switch is actuated to open the motor circuit.

5. In a ventilating appliance of the character described, the combination of a frame, a group of shutter vanes hinged in said frame, a fan mounted behind said vanes, an electric motor for operating said fan, a switch controlling the circuit of said motor, and mechanism actuated by an element of said switch serving to lock said vanes in closed position when said switch is actuated to open the motor circuit and to release said vanes when said switch is actuated to close the motor circuit.

6. In a ventilating appliance of the character described, the combination of a frame, a group of horizontal shutter vanes hinged in said frame, a fan mounted behind said vanes, an electric motor for driving said fan, a vertically disposed link lying behind and crosswise of said vanes, means connecting said link to said vanes to effect simultaneous and equal movements of the latter, a switch controlling the circuit of said motor, a shaft connected to and operated by the button of said switch, and a lifting and locking bar fast on said shaft underlying the lower end of said link; said bar operating to raise said link and hold the same in raised position when said switch is actuated to open the motor circuit, and to release said locking bar when said switch is actuated to close the motor circuit.
